UNITED STATES PATENT OFFICE.

GEORGE M. BLACKWELL, OF DENVER, COLORADO, ASSIGNOR TO THE B AND G DISPLAY COMPANY, OF DENVER, COLORADO, A CORPORATION OF COLORADO.

DISPLAY ATTACHMENT FOR CANDY BOXES.

Application filed June 18, 1927. Serial No. 199,663.

This invention relates to improvements in the construction of display attachments for candy caddies of the type described and claimed in my copending application, Serial No. 163,674, filed on January 26, 1927.

In the vending of candy and all other food products, it is essential that the greatest precautions shall be taken to keep the food clean, it is therefore customary to pack the goods in sealed packages, at the factory, which assures that they will not become soiled or contaminated from the handling that they must receive before they arrive at the ultimate consumer.

In the sale of candy, it has been found to be quite satisfactory and desirable to pack a certain weight into a paper bag which is then sealed. The customer, however, naturally desires to see the goods that he buys or at least to see samples.

It is the object of this invention to produce an attachment that can be applied to the ordinary candy caddies and which consists, first, in a removable liner or collar that can be inserted in a caddy and which is provided with an inwardly extending flange on which a false bottom may be supported. A shallow rectangular box whose length is equal to the width of the caddy is provided at its ends with extensions that hook over the upper edges of the caddy. This box has a removable glass cover and serves as a container for the display of the samples. A frame of the same size and shape as the caddy is secured to the upper ends thereof and serves to hold the box in place and to give the caddy a finished appearance. The candy already packed in bags is stored underneath the false bottom and a few bags are supported on the false bottom so as to be conveniently accessible for immediate delivery to the customer.

In order more clearly to describe my invention, reference will now be had to the accompanying drawing in which it has been illustrated and in which:

Fig. 1 is a top plan view of my improved caddy with parts broken away to better disclose the construction;

Fig. 2 is a section taken on line 2—2, Fig. 1; and

Fig. 3 is a section taken on line 3—3, Fig. 2.

Numeral 1 designates an ordinary paper candy caddy whose bottom is designated by

numeral 2. The caddy is of rectangular shape and the upper edges of the sides are bent outwardly and downwardly as indicated by numeral 3. A frame of the same size and shape as the caddy is provided with 60 sides 4 that extend downwardly over the upper end of the box. This frame has an inwardly extending flange 5 that covers the upper edge of the caddy. A shallow rectangular box 6 extends transversely of the 65 caddy along one side thereof. This box is provided at each of its ends with an extension 7 which projects over the upper edge of the caddy and serves to support the box 6. The ends 8 of the extensions are preferably 70 bent downwardly so as to form hooks (Fig. 3). The sides of box 6 are provided along their upper edges with rabbets 9 in which rests the rectangular glass 10. Samples of the candy are placed within the shallow box 75 6 and can be seen through the glass cover 10.

The caddy is provided with a removable liner 11 that is formed from a single piece of cardboard, and which has its upper edges bent inwardly so as to form a flange 12 that 80 serves as a support for the false bottom 13. The false bottom divides the interior of the caddy into two compartments. The compartment underneath the bottom 13 is used for storing the candy bags and the space 85 above contains one layer of bags or packages from which sales are made. When the supply in the upper compartment has been sold, the false bottom is raised and a new supply transferred to the upper chamber. For convenience in raising the bottom 13, it has been provided with a notch 14. The liner 11 can be made from a single piece of ordinary one-ply stiff cardboard bent into proper shape, but the false bottom 13 should 90 be made of cardboard having a corrugated center.

It will be seen from the above that by means of my simple attachment it is possible to convert an ordinary cardboard candy 100 caddy into a neat appearing display device that is of great convenience in dispensing the candy or other goods. The false bottom makes it possible to give the caddy the appearance of being full, regardless of the 105 amount of goods contained in the lower compartment.

Having described the invention what is claimed as new is:

1. A display device comprising, in combi- 110

- nation, a caddy having a supporting flange on its inside, said flange being located near the top, a false bottom member resting on said flange for supporting sample packages, 5 a display box resting on the upper edge of the caddy along one edge thereof, and a frame telescopically secured to the open end of the caddy, said frame serving to hold the caddy in a predetermined shape and to hold 10 the display box in place and being open for display purposes.
2. A display device comprising, in combination, a caddy having a removable liner whose upper edge is bent inwardly so as to 15 form a supporting flange, a false bottom engaging said flange, and forming a support for sample packages, a display box extending along one side of the caddy, said box having means at its end for engaging the 20 edges of the caddy and a rigid frame tele-

scopically connected with the upper edges of the caddy, said frame serving to hold the display box in place and for holding the caddy in shape and being open for display purposes.

25

3. A display device comprising in combination a caddy having vertical sides, a frame surrounding the outside of the caddy adjacent its top and having a portion extending inwardly over the upper edge of the caddy, 30 a display box supported on the upper edge of the caddy and having means for supporting a glass cover thereon, the inwardly extending portion of the frame serving to hold the glass cover of the box in place, the 35 said frame being also open to display the contents of the box.
